UNITED STATES PATENT OFFICE.

CHESTER MCKAY, OF GLENBROOK, CONNECTICUT.

GAME.

Application filed August 11, 1921. Serial No. 491,408.

To all whom it may concern:

Be it known that I, CHESTER MCKAY, a citizen of the United States, residing at Glenbrook, in the county of Fairfield and 5 State of Connecticut, have invented certain new and useful Improvements in Games, of which the following is a full, clear, and exact specification.

This invention relates to games, and has 10 for its object to provide a novel and improved form of game board on which detachable strips or sheets may be used for marking progressive plays, thereby dispensing with the use of game pieces generally employed for this purpose.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout 25 the several views:

Figure 1 is a plan view of a game board constructed substantially in accordance with this invention, showing the positions of the detachable strips in dotted lines.

30 Figure 2 is an edge view of the board.

Figure 3 is a detailed plan view of one of the detachable strips, and

35 Figure 4 is a detailed perspective view of one form of clip for holding the detachable strips in position on the board.

The game board 1 may be made of any suitable material, such as wood, cardboard, or the like, and its dimensions may be varied to suit requirements. On the surface of the 40 board a series of segmental paths 2 are printed, or otherwise marked, and said paths are uniformly divided into concentric spaces 5 by a series of concentric arcs 9, a circular space 4 being left blank in the center of the board. Through the axis of each of the segmental pairs, which are separated from one another by radial lines 6, extends a radial blank space 3 leaving from the margin of the board to the central space 4.

50 In radial alinement with the spaces 3, starting points for the players may be indicated on the marginal portion of the board by squares marked "A", "B", "C" and "D". On certain of the concentric spaces 5 directions for governing the plays may be indicated, such as "Pay 4 counters" and "Collect

3 counters", as shown in Figure 1. It will be understood that these directions are arbitrary and may be changed without departing from the invention, and that any or all 60 of said concentric spaces 5 may be marked with similar directions, or some of said concentric spaces left blank, as illustrated.

Before commencing play paper strips 8 are placed along the radial spaces 3, as indicated in dotted lines in Figure 1, said strips 8 crossing one another in the central space 4 and being detachably fastened at their ends to the board by clips 7 of any suitable construction. As shown, the clips 7 65 70 are made of corrugated wire having their extremities inserted in the surface of the board 1 and their intermediate portions provided with a series of paper clamping points or teeth 10. Said points or teeth may be 75 readily raised with the finger when the ends of the strips 8 are to be placed thereunder, and the resiliency of said clips will clamp said strips to the board when released.

Any suitable form of spinner, dice, or 80 other indicator device may be used to designate by chance the number of spaces to be moved by each player in turn, but instead of game pieces or "men" being used for indicating the progressive plays, each player 85 places his mark on the cover strips or sheet of paper on the board by means of a pencil, rubber stamp, or other device. The play starts at the outer edge of the segments or paths 2, one of which may be used by each 90 player, and the progressive plays are counted off on the concentric spaces 5 from the outer edges of said segments toward the central space 4. If a play terminates on one of said concentric spaces 5 bearing the directions "Pay 4 counters" or "Collect 3 counters", or any other directions which may be used, the player must comply with said directions, payment being made or collected from a supply of counters of any suitable 95 form which are equally distributed among the players at the start of the game.

The object of the game is to win all the counters from the other players, and this may be done in various ways according to 100 any set of rules which may be adopted. For instance, if a move of one player brings him to a space occupied by another player, said other player may be required to retire from the board and also forfeit an agreed 110 number of counters to the first player. When each player reaches the central space

4 on the board via his own segmental path
2, he may be permitted to select any of the
other players' segmental spaces for travel
back to the margin of the board, such se-
lection being made according to the positions
5 of the other players' marks on their respec-
tive paths and the apparent chances of win-
ning counters from them as just explained,
and also by the chances of his escaping cap-
10 ture himself.

After each game, the paper strips 8 are
removed and the new set substituted there-
for for receiving the players' marks in a new
game.

15 I claim:

1. A game board having an annular se-

ries of segmental paths, each path having a
blank space extending radially therethrough,
paper strips to overlie said blank spaces and
means arranged at the outer ends of said 20
radial spaces for detachably securing said
strips of paper over the same to receive
marks for indicating the plays.

2. The combination with a game board
having an annular series of segmental paths, 25
of paper strips, and means for detachably
securing said strips to extend radially across
said segmental paths to receive marks for
indicating the plays.

In testimony whereof I have signed my 30
name to this specification.

CHESTER MCKAY.
